US00D596029S

(12) **United States Design Patent**
Parve

(10) **Patent No.:** **US D596,029 S**
(45) **Date of Patent:** **** Jul. 14, 2009**

(54) **CLOSURE FOR A CONTAINER**

3,018,931 A 1/1962 Westgate

(75) Inventor: **Terrence M. Parve**, Menomonee Falls, WI (US)

(Continued)

(73) Assignee: **Gateway Plastics, Inc.**, Mequon, WI (US)

OTHER PUBLICATIONS

(**) Term: **14 Years**

(21) Appl. No.: **29/312,897**

(22) Filed: **Aug. 1, 2008**

Graphic Images: Closure #2, 1 page.

(Continued)

Related U.S. Application Data

(63) Continuation of application No. 29/261,784, filed on Jun. 20, 2006, now abandoned.

Primary Examiner—Susan Bennett Hattan

(74) *Attorney, Agent, or Firm*—Foley & Lardner LLP

(51) **LOC (9) Cl.** **09-07**
(52) **U.S. Cl.** **D9/453; D9/499**

(57) **CLAIM**

(58) **Field of Classification Search** D9/454, D9/450, 449, 447, 446, 428, 435, 423, 421, D9/420, 453; D7/900, 401.1, 396.1, 392; 229/207; D6/518; D34/11, 7, 13; D3/323; 222/480, 256; 220/812, 810, 480, 345.1, 220/256.1, 253, 213, 322, 306, 236, 235

FIG. 1 is a top perspective view of the closure for a container;

FIG. 2 is a bottom perspective view of the closure for a container;

FIG. 3 is a top view of the closure for a container;

FIG. 4 is a front view of the closure for a container;

FIG. 5 is a bottom view of the closure for a container;

FIG. 6 is a left side view of the closure for a container, the right side view being a mirror image;

FIG. 7 is a top perspective view of the closure for a container in an open position;

FIG. 8 is a top view of the closure for a container in an open position;

FIG. 9 is a detailed top view of a portion of the closure for a container, taken at the area marked 9—9 on FIG. 8;

FIG. 10 is a front view of the closure for a container in an open position; and,

FIG. 11 is a left side view of the closure for a container in an open position, the right side view being a mirror image.

The broken lines in the drawings are for illustrative purposes only and form no part of the claimed design.
